ATTORNEY

UNITED STATES PATENT OFFICE.

FREDERICK G. FRANKENBERG, OF ST. LOUIS, MISSOURI, ASSIGNOR OF
TWO-THIRDS TO MARY C. METCALFE, OF SAME PLACE.

DESIGN FOR A VAPOR-LAMP.

SPECIFICATION forming part of Design No. 30,767, dated May 16, 1899.

Application filed March 24, 1899. Serial No. 710,383. Term of patent 3½ years.

To all whom it may concern:

Be it known that I, FREDERICK G. FRANKENBERG, a citizen of the United States, residing in the city of St. Louis, State of Missouri, 5 have invented and produced a new and original Design for Vapor-Lamps, of which the following is a specification.

The figure is a front elevation of a vapor-lamp embodying my new and original design.

10 As shown in the drawing, the leading or essential feature in my new design consists of the hook 1, the cylindrical tank 3, the pipe extending through the tank and having the end 2 above the tank and connecting with 15 the hook, and the end 4, extending downwardly from the tank, the T-joint 5 upon the lower end of said pipe, the pipes 6 and 7, extending in opposite directions from the T-joint, the valves 8 and 9 upon the outer ends of said

20 pipes 6 and 7, the elbow-pipes 10 and 11, extending outwardly and downwardly from the valves 8 and 9, respectively, the pipe-couplings 12 and 13, extending downwardly from said elbows, the U-shaped generators 14 and 15, extending horizontally from said pipe-couplings, and the irregularly-shaped mixing-chambers 16 and 17, extending downwardly from said pipe-couplings and having 25 elbows extending upwardly from their lower ends.

30

I claim—

The design for a vapor-lamp, substantially as herein shown and described.

FREDERICK G. FRANKENBERG.
